UNITED STATES PATENT OFFICE.

ROY L. SPAULDING, OF HELENA, MONTANA.

ATTACHMENT FOR DENTAL ENGINES.

1,268,171.

Specification of Letters Patent. Patented June 4, 1918.

Application filed April 14, 1917. Serial No. 162,031.

To all whom it may concern:

Be it known that I, ROY L. SPAULDING, a citizen of the United States, residing at Helena, in the county of Lewis and Clark 5 and State of Montana, have invented certain new and useful Improvements in Attachments for Dental Engines; and I do hereby declare the following to be a full, clear, and exact description of the invention, 10 such as will enable others skilled in the art to which it appertains to make and use the same.

My invention relates to an improved attachment for dental engines, and more particularly to a mandrel for holding spiral or 15 other broaches or small reaming instruments used in opening and cleaning the canals of teeth and which is capable of efficient use in connection with straight or any angle dental 20 engine hand piece.

One of the aims of this invention is to provide a mandrel whereby the broach or other instrument is inserted through the mandrel from its inner end in a manner 25 that the operating end of the instrument may be projected at any desired distance from its other end and secured in the latter end in an efficient manner but not sufficiently rigid to prevent the instrument from rotating 30 in the mandrel should the instrument encounter an obstruction sufficient to break the instrument off in the tooth, which accident often happens when the instrument is rigidly secured in the hand piece as is now 35 the common practice.

With these objects in view, the invention consists in the improved construction, arrangement, and combination of parts hereinafter fully described, and afterward specifically claimed.

In order that the construction and operation thereof may be readily comprehended, an approved embodiment of the invention is illustrated in the accompanying drawings, 45 and will be fully described, having reference to said drawings, in which—

Figure 1 is a side elevation of the invention.

Fig. 2 is a similar view to Fig. 1, except 50 in the compression nut is shown in section.

Fig. 3 is an end view of the device.

Fig. 4 is an end view of the mandrel with the compression nut removed.

55 Fig. 5 is a fragmentary side elevation of the inner end of the mandrel showing the

same as turned to a position at right angles to the position of the mandrel shown in Figs. 1 and 2.

Fig. 6 is an end elevation of the inner 60 end of the mandrel with the compression nut removed.

Referring to the drawings, wherein similar reference characters denote corresponding parts throughout the several figures, 1 65 denotes the mandrel provided with the central bore 2 extending longitudinally therethrough from end to end. The mandrel 1 is provided with an enlarged portion 3 upon which are formed screw threads 4 and with 70 a cone shaped end 5. Extending radially from the bore 2, through the enlarged portion 3 of the mandrel 1, are the slots 6, preferably three in number, whereby the enlarged body portion 3 of the mandrel 1 consists of the three flexible gripping prongs 75 7 for gripping the dental instrument (not shown) which is projected through the bore 2 from its inner end and its operating end extending for a distance beyond the cone 80 shaped end 5.

To cause the flexible prongs 7, to grip the instrument or tool within the bore 2, the nut 8 is provided, having internal threads 9 for engaging the threads 4 of the mandrel 85 1 and also an enlarged milled or knurled head 10 whereby to turn the nut 8 upon the threads 4. Upon the nut 8 is formed the hollow frusto-conical sleeve 11, so that when the nut 8 is screwed inward upon the threads 90 4 of the mandrel 1, the inner inclined wall of the sleeve 11 will ride upwardly upon the inclined surfaces of the prongs 7, and force the prongs inwardly to clamp the tool.

To attach the inner end of the mandrel 1 95 to the hand piece of a dental engine, which hand piece may be in the form of a straight or angle hand piece, the inner end of the mandrel 1 is formed with the annular groove 12 providing the head 13, which head 13 and the adjacent portion of the mandrel 1 are longitudinally cut away to provide the flat base 14 and the shoulder 15 whereby to secure this end of the mandrel 1 within a corresponding socket formed in the operating 100 mechanism carried by the hand piece of the dental engine.

From the foregoing it will clearly be seen that I have produced a device which is capable of being readily attached to or detached from the operating mechanisms carried by the hand piece of a dental engine,

which hand piece, may be of the direct or straight type or which may be of any angle type, and that by providing this mandrel with its central longitudinal bore therethrough a dental tool may be secured upon the mandrel with any desired portion of its operating end projecting at any desired distance from the end of the mandrel, so that by adjusting the tool in the mandrel any desired length of 10 tool may be attained to accommodate the same to the various uses and positions for operating upon a tooth and which tool may be directed in any desired direction with relation to the tooth being operated upon. 15 Furthermore, in providing this mandrel, a tool can be sufficiently rigidly secured in the mandrel for ordinary purposes, and at the same time should the tool be subjected to such excessive strains is capable of sufficient 20 rotary movement within the mandrel as to prevent breaking.

While I have herein disclosed one form of my invention I may resort to variations and modifications in the construction of the various parts thereof to meet the exigencies of a given case without departing from the spirit of the invention as claimed.

Having described my invention, what I

claim as new and desire to secure by Letters Patent, is:—

The mandrel herein described provided with a central bore extending longitudinally therethrough from end to end and having an enlarged, externally threaded portion terminating in a conical end, the enlarged portion, including the conical end, being radially slotted, a sleeve nut having a threaded bore to fit upon the threads of the mandrel with its bore reduced from the screw-threaded portion to its outer end forming said 40 outer end into a frusto-conical sleeve to bear on the split conical outer end of the mandrel, the longitudinal bore being adapted to receive a tool at its inner end to be projected out beyond its outer end and gripped by the 45 radially slotted head, and means at the inner end of the mandrel to secure it to the hand piece of a dental engine.

In testimony whereof I have signed my name to this specification in the presence of 50 two subscribing witnesses.

ROY L. SPAULDING.
